US00D792408S

(12) **United States Design Patent** (10) **Patent No.:** **US D792,408 S**
(45) **Date of Patent:** **** Jul. 18, 2017**

(54) **HANDLE FOR MOBILE COMPUTER**

(71) Applicant: **GETAC TECHNOLOGY CORPORATION**, Hsinchu County (TW)

(72) Inventors: **Hsiu-Yu Kuo**, Taipei (TW); **Ying-Chun Chen**, New Taipei (TW); **Chia-Hsien Lin**, Taipei (TW)

(73) Assignee: **Getac Technology Corporation**, Hsinchu County (TW)

(**) Term: **15 Years**

(21) Appl. No.: **29/539,844**

(22) Filed: **Sep. 17, 2015**

(51) LOC (10) Cl. **14-02**

(52) U.S. Cl.

USPC **D14/432**

(57) **CLAIM**

The ornamental design for a handle for mobile computer, as shown and described.

DESCRIPTION

FIG. 1 is a top front right perspective view showing a first embodiment of my new design;

FIG. 2 is a bottom front left perspective view showing a first embodiment of my new design;

FIG. 3 is a top rear left perspective view showing a first embodiment of my new design;

FIG. 4 is a front view of the first embodiment of my new design;

FIG. 5 is a rear view of the first embodiment of my new design;

FIG. 6 is a left side view of the first embodiment of my new design;

FIG. 7 is a right side view of the first embodiment of my new design;

FIG. 8 is a top view of the first embodiment of my new design;

FIG. 9 is a bottom view of the first embodiment of my new design;

FIG. 10 is a top front right perspective view of the first embodiment of my new design installed on a mobile computer;

FIG. 11 is a top front right rear perspective view showing a second embodiment of my new design;

FIG. 12 is a bottom front left perspective view showing a second embodiment of my new design;

FIG. 13 is a top rear left perspective view showing a second embodiment of my new design;

FIG. 14 is a front view of the second embodiment of my new design;

FIG. 15 is a rear view of the second embodiment of my new design;

FIG. 16 is a left side view of the second embodiment of my new design;

FIG. 17 is a right side view of the second embodiment of my new design;

FIG. 18 is a top view of the second embodiment of my new design;

FIG. 19 is a bottom view of the second embodiment of my new design; and,

FIG. 20 is a top front right perspective view of the second embodiment of my new design installed on a mobile computer.
